MACHINE FOR ROUGHING SHOE PARTS

Charles G. Brostrom, Lynn, Mass., assignor to
United Shoe Machinery Corporation, Paterson,
N. J., a corporation of New Jersey

Application October 20, 1931, Serial No. 569,938

6 Claims. (CL 51—57)

This invention relates to machines for and methods of roughing or abrading parts of boots and shoes or the like, and particularly to machines for removing the finished surface of leather pieces preparatory to attaching them by cement.

While the machine is adapted for a wide range of use, a field of particular importance is in preparing the bottom of a lasted shoe and the corresponding outsole to receive cement in the manufacture of shoes of those types in which cement is relied upon wholly or principally for attaching the outsole. It will be understood that the bond between the cement and these leather parts of the shoe is improved and made more secure if the finished surface of the leather is removed or roughened preparatory to the application of cement. In one aspect, accordingly, my invention consists in a machine adapted for roughing the marginal portion of the inturned upper of a lasted shoe and it includes within its scope a novel method of performing this operation.

It is difficult to gauge accurately a roughing operation upon the bottom of a lasted shoe from the peripheral edge thereof, particularly on account of the curvature of the last in the shank of the shoe. I have discovered that the roughing operation may be satisfactorily gauged from the inner edge of the over-wiped upper material upon the shoe bottom. An important feature of my invention, therefore, consists in a roughing machine having a gauge adapted to run upon the insole of an inverted shoe in contact with the inner edge of the inturned upper material, in combination with a vibratory roughing tool movable in a path parallel to the effective face of the gauge and in predetermined relation thereto. Such a construction permits the operator to present the bottom of a lasted shoe accurately to the operation of the roughing tool and advance the same in a controlled path bringing all areas of the shoe bottom, which are to be roughened, progressively into the range of the roughing tool.

The construction above discussed is not well adapted for handling an outsole or other flat piece and, accordingly, alternative work supporting and gauging mechanism is provided for adapting the machine for such a field of use. Such mechanism preferably includes a flat work table and related edge gauge which are constructed and arranged to be substituted as a unit for the shoe bottom gauge mechanism.

Other features of the invention relate more

particularly to the construction of a novel roughing tool which has been found particularly efficient in its abrading action and convenient in use. I prefer to employ an abrasive band or strip and to support the operative portion thereof upon a curved yielding backing. For this purpose, a roll is preferably utilized and in addition to the function of shaping and supporting the abrasive band, it may be utilized also as one element of feeding mechanism for advancing the band when it is desired to renew the operative portion thereof. The roughing tool of my invention includes also novel means for shaping the abrasive band into the form of a loop and guiding it about the supporting roll. By giving the abrasive band a loop-shaped form, it may be conveniently and securely held in position upon the supporting roll and it may also be fed with rapidity and accuracy when this is desired. Accordingly, another important feature of my invention consists in a vibratory roughing tool including in its structure means for shaping and for feeding an abrasive band.

It is important to reduce the time required for feeding the band in renewing the same as the time thus consumed reduces the output of the machine. An important saving in this respect may be effected by arranging the band feeding mechanism to operate without the necessity of stopping the vibration of the abrading tool. With these conditions in view, another feature of the present invention consists in the combination with a vibratory roughing tool embodying an abrasive band with mechanically operated feeding mechanism controlled by the operator and arranged to act during the movement of the tool.

These and other features of the invention will be best understood and appreciated from the following description of a preferred embodiment thereof, selected for purposes of illustration and shown in the accompanying drawings, in which:

Fig. 1 is a view of the machine head in side elevation;

Fig. 2 is a sectional view of the ratchet mechanism on the line 2—2 of Fig. 1;

Fig. 3 is a view of the machine head in front elevation;

Fig. 4 is a detail view, partly in section on the line 4—4 of Fig. 1, of the rocker member and associated parts;

Fig. 5 is a detail view of the abrasive tool, partly in section on the line 5—5 of Fig. 1;

Fig. 6 is a view in perspective of a sole

lustrating the character of the work done by the machine;

Fig. 7 is a sectional view of the machine head on an enlarged scale, on the line 7—7 of Fig. 3, 5 showing an alternative form of gauge; and

Fig. 8 is a sectional view on the line 8—8 of Fig. 7, on an enlarged scale illustrating the mounting of the rocker or carrier member.

The machine of my invention, with appropriate adaptation, may be utilized for roughing or for buffing various parts of boots and shoes at different stages in the manufacture thereof. By way of illustration, the machine as shown in Figs. 1 and 2 is provided with a work table and 10 thus adapted for roughing soles or other flat shoe parts. In Fig. 7 it is shown as provided with a gauge for cooperating with the inner sole of a lasted shoe and thus adapted for roughing the inturned upper material preparatory to coating it with cement. It will be apparent that the machine may be equipped with other appropriate work supports or gauges adapting it to operate 15 upon other shoe parts as may be desired.

The machine head is supported upon a column 25 at a convenient height for the operator and comprises a casting provided with bearings for a main shaft 14 which is provided with an intermediate driving pulley 16 and, at one end, with an eccentric portion arranged to oscillate a horizontally disposed link 18. The forward end of the link 18 is connected to a vertically disposed rocker member comprising an upper arm 20 and a lower arm 21. The rocker member is mounted, as best shown in Fig. 8, upon a transverse journaled pin 24. The lower arm 21 of the rocker member is yoke-shaped and receives a spring bracket arm 28 which carries at its free end a hardened member 26 provided in its upper face with a semi-cylindrical bearing surface adapted to receive and support the journal pin 24. The rocker member, on the other hand, is provided with a fiber block 22 having formed in its lower surface a corresponding cylindrical bearing surface also fitting the journal pin. The spring bracket arm 28 bears against 45 the flange of the head casting 12 at its outer end and is adjustably maintained in place by a clamping bolt 29.

The lower arm 21 of the rocker member is provided at each side with shoulders 32 which have upwardly convex cam surfaces and these are arranged to bear against the lower plane faces of fiber blocks 30 secured to the head casting 12. The engagement of the shoulders 32 with the fiber blocks 30 positively determines the 50 position of the rocker member 20—21 and the degree of pressure of these shoulders upon the fiber block is determined by the spring of the bracket arm 28 as adjusted by the bolt 29. The curvature of the cam surfaces is such as to depress the rocker member bodily as it swings in either direction from its central position an amount sufficient to maintain its lower end travelling in a straight line path. Suitable passages are provided in the upstanding arm 20 of the 55 rocker member for lubricating the bearing member 24. The construction above described is one which is particularly satisfactory for high speed oscillation or vibration of relatively short amplitude, and while it is desirable and contributes 60 to the efficiency and smooth running of the machine, it is not, in its specific form, an essential feature of my invention.

In the machine herein illustrated, the rocker member 20—21 carries and forms a part of the 70 abrading or roughing tool. To this end a car-

rier member 34 having upwardly extending arms 36 and 38 is securely bolted to the lower arm 21 of the rocker member by clamping bolts 39 as best shown in Fig. 7. The carrier member 34 is provided with elongated bearings for a horizontal ratchet shaft 40 provided at its rear end with a ratchet disk 42 and a toothed flange 46, the latter cooperating with a pair of spring actuated detents 44 suitably mounted in sockets in the carrier member 34. The detents 44 and toothed flange 46 serve to hold the ratchet shaft normally at rest, although the detents yield to permit it to be rotated at times by the ratchet disk 42, as will presently appear.

At its forward side the carrier member is provided with a thick cover casting 48 flanged at its edges and attached to the face of the carrier member by screws 50. The cover casting 48 closes a chamber which is formed in the forward face of the carrier member 34 and in which is provided a pinion 52 pinned to the ratchet shaft 40 and rotatable therewith. The cover casting 48 is also provided with a bore for the reception of the forward end of the ratchet shaft 40 which, as will be noted, is provided with a square section 41 to fit a socket wrench whereby the ratchet shaft may be manually rotated whenever this may be desirable as in setting up the machine or leading in the abrasive band. The cover casting 48 is provided also with upper and lower bearings for an upper roll shaft 54 and a lower roll shaft 62 respectively. The upper roll shaft 54 is provided with a pinion 56 meshing with the pinion 52 on the ratchet shaft 40. The shaft 54 extends rearwardly into a bushed bearing in the carrier member 34 and forwardly into a recess in the face of the casting 48 where it is provided with a rubber roll 58 secured in place by a clamping nut 60. The roll 58 has the functions of a friction member in holding the abrasive band in place and also of a feeding member, as will presently appear.

The lower roll shaft 62 is of smaller diameter and is arranged to slide longitudinally in the elongated hub 64 of a pinion 65 which meshes with the pinion 52 of the ratchet shaft. The hub 64 of the pinion is journaled in a bushed bearing in the lower portion of the carrier member 34 and is provided with a transverse slot in its outer end in which slides a cross-pin 66 which is set in the shaft 62. This shaft, therefore, is driven by the pinion 52 but is movable axially or longitudinally with respect thereto. The forward end of the shaft 62 is enlarged and between this portion thereof and the face of the pinion 65 is interposed a compression spring 68 which tends at all times to urge the shaft forwardly. At its forward end the shaft 62 is arranged to slide in the bore of the lower rubber roll 70. The latter is provided with an elongated hub 60 and this is journaled in the lower bearing of the casting 48. The roll 70 has a cross-pin 69 extending across its bore and the forward end of the shaft 62 is slotted freely to receive the same. By this means, therefore, a positive driving connection is maintained between the shaft 62 and the lower rubber roll 70. The rear end of the shaft 62 projects beyond the end of the hub 64 and is provided with a knurled portion by which it may be conveniently grasped and retracted when it is desired to release the lower rubber roll 70 for the purpose of removing the latter for replacement or renewal. It will be seen that both rubber rolls are turned equally and in the same direction by their geared con-

nection with the ratchet shaft 40 whenever the latter is rotated. A cover plate 49 is secured by screws 51 to the front face of the casting 48 and serves to inclose the upper rubber roll 58 and the lower rubber roll 70 except for the lower segment thereof.

The lower rubber roll 70 constitutes a yielding backing member for shaping, supporting, and feeding an abrasive band 72 by which the actual abrading or roughing operation is performed. A relatively large supply of the abrasive band 72 is maintained in the form of a coil in a reel 74 supported by a bracket 76 secured to and projecting upwardly from the head casting 12. The reel 74 may be of any suitable construction and forms no part of the present invention. It is, however, provided with an adjustable tension device 78 by which its rotation is retarded so that it will not overrun the band 72 as the latter is drawn therefrom.

The band 72 passes downwardly from the reel 74 and is threaded between the upper rubber roll 58 and a smaller rubber guide roll 80 which is maintained in yielding engagement with the outer side of the larger roll. Thence the abrasive band passes vertically downwardly, about the lower rubber roll 70, thence upwardly past the other side of the upper rubber roll 58 and finally to a serrated blade 77 which is carried by the bracket 76 and against which the surplus used portion of the band may be torn off.

At its left hand or delivery side, the upper roll 58 is provided with a second rubber guide roll 84 similar to the roll 88 already mentioned and located oppositely thereto. The guide roll 80 is mounted near the upper end of a vertically disposed arm 81 and the guide roll 84 in a similarly arranged arm 85. The arm 81 is journalled to swing upon a pin 82 and is provided at its lower end with a finger piece 83. The arm 85 is pivoted to swing upon a pin 86 and provided at its lower end with a finger piece 87 in alignment with and oppositely directed from the finger piece 83. The upper ends of the arms 81 and 85 are hook-shaped and connected by the tension spring 88 which acts normally to swing the arms inwardly and maintain the abrasive strip 72 yieldingly engaged between the respective guide rolls and the opposite sides of the upper roll 58. When for any reason it is desired to swing the guide rolls outwardly, as in threading the abrasive band into the machine, the finger pieces 83 and 87 may conveniently be pressed together and the arms swung outwardly in opposition to the spring 88. The action of the rolls 80 and 84 is to maintain the abrasive band evenly and yieldingly drawn with a suitable degree of tension about the periphery of the lower rubber roll 70 so that the band will be maintained smoothly and securely in position during the rapid vibration of the abrading tool. The rolls cooperate not only to shape a portion of the abrasive band into loop form, but to maintain it in this condition so that it is effective in a more or less flattened arc efficiently to perform an abrading or roughing operation upon the work presented to it.

An auxiliary bracket casting 100 is bolted to the right hand side of the column 10, as best shown in Fig. 1. This is provided with a forwardly extending arm 101 in the outer end of which is mounted a work support, to be presently described. The bracket also carries a portion of the band-feeding mechanism, that is to say, the

element by which the latter is thrown into operation.

It will be apparent that, in as much as the effective area of the abrasive strip is limited, the operative portion thereof must be renewed frequently. To take care of this requirement, manually operated means are provided for causing the power actuation of the ratchet shaft 40 whenever desired. A hand lever 90 is pivotally connected to the bracket 100 within convenient reach of the operator and is yieldingly connected through a slotted link 91 to the forward end of a carrier arm 92 journalled to swing vertically upon a stud 93 projecting from the upper part of the bracket. The arm 92 extends above and in vertical alignment with the ratchet disk 42 and is provided with a pawl 94 which may be brought into engagement with one of the ratchet teeth by swinging the arm 92 downwardly in a counter clock-wise direction. The hand lever 90 is normally elevated by a tension spring 95 and accordingly holds the lever 92 in an elevated position wherein the pawl 94 is disengaged from the teeth of the ratchet disk 42. However, when the operator depresses the lever 90, the pawl 94 engages a tooth of the ratchet disk as the latter is bodily moved back and forth with the carrier member 34 and the effect thereof is to advance the ratchet disk one step at a time, correspondingly turning the rubber rolls 58 and 70 and advancing the abrasive strip so as to bring a fresh portion thereof into operative position upon the lower roll 70. When such feeding movement of the band has occurred, the operator releases the lever 90 and the pawl 94 is immediately disengaged from the ratchet disk 42, leaving a fresh portion of the abrasive band clamped in operative position.

The machine as shown in Figs. 1 and 3 is equipped with a flat work table 102 adapting it for operating upon an outsole 130 or any other substantially flat piece of work. The table 102 has a downwardly extending shank portion by which it is securely bolted by a clamping bolt 103 to the front end of an angular bracket 104. The bracket is pinned to the upper end of a stem 106 and the latter is mounted to slide in a vertical bore formed in the forward end of the arm 101 of the bracket 100. A tension spring 108 normally elevates the bracket 104 and the gauge table, the upward limit of its movement being determined by an adjustable collar 110 secured to the lower end of the stem 106. The bracket 104 and the work table may be lowered by the operator in presenting the work to the machine by a tread rod 112 which is pivotally secured to the lower end of the stem 106. The bracket 104 is provided in its upper face with a guideway in which is mounted a slotted edge gauge slide 114. The slide carries an edge gauge roll 118 which is disposed adjacent to the rear edge of the work table 102 and arranged to rotate about a vertical axis in contact with the edge of the work. A clamping bolt 116 is provided by which the edge gauge slide 114 may be clamped in any desired position of adjustment. The edge gauge 118 is located directly behind the roll 70 when the latter occupies its central position. The path of the reciprocating abrading tool is, therefore, disposed directly in front of the operative point of the gauge.

When it is desired to utilize the machine for roughing the bottom of a lasted shoe, preparatory to receiving cement in attaching an outsole thereto, the bracket 104 together with the

work table 102 and its associated parts are removed from the machine and a gauge of the character shown in Fig. 7 is substituted therefor. When thus equipped, the machine is provided with a gauge arm 120 which is clamped in any convenient manner to the reel bracket 76 and which extends downwardly in front of the abrading tool. The arm 120 is provided with a vertically disposed groove which is closed by a cap plate 126 and forms a guideway for a gauge slide 122. The latter is inclined inwardly at its lower end and is provided with a gauge wheel 124 adapted to run on the surface of the insole of an inverted shoe when the latter is presented to the roughing tool. A tension spring 128, extending between a pin in the cap plate 126 and a pin in the gauge slide, holds the gauge normally in its lowermost position but permits it to yield upwardly when engaged by the shoe. As shown in Fig. 7, the last 136 carries an insole 134 on its tread face and the upper material 138 has been over-wiped and secured to the face of the insole by staples, tacks, or other fastening means. The gauge wheel 124 is positioned vertically by its engagement with the surface of the insole 134 and it acts to position the lasted shoe width-wise with respect to the abrasive tool by engaging the edge of the in-turned upper material, or the crease between this material and the insole. As the shoe is advanced by the operator, its path is determined by the gauge wheel 124 and the over-wiped margin of the upper material is subjected to the rubbing action of the abrasive band carried by the roughing tool. The roughing operation proceeds in this manner about the periphery of the shoe removing the finished surface from the leather and permitting the later applied cement to form a firm bond with the upper material.

In operating upon an outsole 130, when the machine is equipped as shown in Figs. 1 and 3, the latter is gauged from its outer edge by the edge gauge roll 118 and a roughened peripheral zone 132 is formed by the action of the roughing tool as the sole is carried through the machine. In completing the shoe, therefore, a firm bond of cement is insured both between the in-turned upper material on the shoe bottom and the surface of the outsole covering the same.

Having thus described my invention what I claim as new and desire to secure by Letters Patent of the United States is:—

1. A machine for roughing shoe parts, com-

prising a vibratory carrier having an outer backing roll for an abrasive band, and an inner feed roll, an abrasive band disposed about the backing roll and in feeding engagement with the feed roll at both sides of the backing roll, means for holding the band against the circumference of the feed roll at diametrically opposite points, and mechanism for rotating said roll to advance the band across the backing roll.

2. A roughing tool comprising a carrier member having a backing roll at its outer end, and means for guiding an abrasive band in a loop about said roll, including a centrally disposed friction member, and releasable presser members arranged to press the band against the opposite sides of said friction member.

3. In a machine for roughing shoe parts, the construction with a vibratory carrier, of a pair of gear-connected rolls therein, an abrasive band passing about said rolls and yieldingly supported in operative position by one of them, and mechanism outside said carrier for controlling, at the will of the operator and without affecting the vibratory movement of the carrier, the rotation of said rolls and thereby the advancing movement of the band.

4. In a machine for roughing shoe parts, a vibratory carrier, a roll therein constructed and arranged to support and feed an abrasive band, a gear train in the carrier for rotating said roll, and means for detachably connecting said roll and train permitting convenient replacement of the roll.

5. In a machine for roughing shoe parts, a vibratory carrier having spaced band positioning and feeding rolls, driving mechanism for the rolls including a gear train and a ratchet disk mounted upon the carrier, and a manually controlled pawl mounted independently of the carrier arranged to be moved by the operator, while the carrier is vibrating, into or out of position to engage and rotate the ratchet disk during the movement of the carrier in one direction.

6. A machine for roughing shoe bottoms, comprising a vertically yielding roller gauge adapted to run upon the insole of an inverted shoe in contact with the inner edge of the in-turned upper material, and a vibratory carrier mounted adjacent to the gauge and having a yielding abrasive-covered face arranged to operate upon the in-turned margin of the upper outside of the gauged edge thereof.

CHARLES G. BROSTROM.
